MATCH PACKET

Alfred Franklin Hedges, Philadelphia, Pa.

Application March 2, 1942, Serial No. 433,067

1 Claim. (Cl. 206—29)

The invention relates to an improved match packet wherein the body of detachable paper matches is swingable relative to the walls of the packet to expose the matches for detachment and use, the body of matches being swingable to restore it in its closed position within said walls, and the primary object of the invention is to provide a simple and efficient arrangement of this character which is more convenient and comfortable in use than prevailing types of match packets.

Other important objects and advantages of my invention will be apparent from a reading of the following description taken in connection with the appended drawing, wherein for purposes of illustration a preferred embodiment of the invention is shown.

In the drawing:

Figure 1 is a general side elevational view of the packet partly broken away to show the position of some of the matches therein, and showing in dotted lines enclosed and exposed positions of the match body.

Figure 2 is a right hand end elevational view of Figure 1.

Figure 3 is a bottom plan view of Figure 2.

Referring in detail to the drawing, the numeral 5 generally designates the improved match packet which comprises the enclosing element 6, which in its most elemental form is an elongated rectangular sheet of paper, cardboard, metal, or plastic or other suitable material folded transversely at its middle to form a relatively widely curved bend 7, and with the ends 8 brought up even with each other. The corners on one end of the edges 8 are cut away as indicated by the numerals 9 to provide convenient access to the match body which is generally designated 10 and which forms the second main component of the packet.

The match body 10 is generally similar to those now in use in paper match packets. This match body consists of the paper matches 11 rising in a double row from the upper edge of horizontally elongated paper or similar material base portions 12 which are reinforced by similarly shaped outside plies 13. In the present instance additional similarly shaped reinforcing strips 14 are placed at the outer sides of the plies 13 to add additional reinforcement and to increase the overall width or thickness of the basal portion of the match body, in the manner exemplified in Figure 2 of the drawing, and thereby provide a relatively wide surface 15 on the bottom of the match body to accommodate a relatively wide and sturdy, and, therefore, efficient match

scratching surface providing member 16. The various plies of the match body may be secured together by present methods or by any suitable means, and the match scratching surface element 16 may be secured to the bottom 15 of the resulting assembly in any suitable manner.

As indicated in Figure 2 of the drawing, the match body is mounted within the enclosure 6 so that when the bottom of the match body is parallel with the lower edges 8 of the enclosure the element 16 will be substantially flush with the lower edges 8.

To mount the match body swingably within the enclosure a suitable low-cost combined securing element and pivot 17 is associated with the match body 10 and with the side walls of the enclosure 6 in a suitable manner, as by passing through these bodies, so that they can swing relative to each other. In the present instance heads 18 may be provided on a wire pivot to engage the outer sides of the side walls of the enclosure to hold the pin in place and the enclosure assembled with the match body.

As indicated in Figure 1 of the drawing, the match body having been properly mounted within the enclosure 6, one corner of the match body projects beyond the cut away portions 9, so that it is a simple and natural maneuver of the fingers of the user to engage the exposed portion 25 of the match body and swing the same into either of the dotted line positions illustrated in Figure 1 of the drawing, wherein the matches 11 are totally exposed and may be easily separated from the match body and the match body returned to 30 the enclosed position wherein the striking surface 16 is safely exposed for igniting the match severed from the match body, by striking the match thereagainst.

Although there is shown and described herein 40 a preferred embodiment of the invention it is to be understood that it is not intended to limit the application of the invention thereto beyond the scope of the subjoined claim.

Having described the invention, what is claimed 45 as new is:

A match packet comprising a hood forming strip folded intermediate the ends thereof to provide spaced apart sides for the hood and opposed parallel ends therefor, a match assembly 50 including match stems, and strip-like filler members arranged in pairs upon opposite sides of the tail ends of said stems and between which said stems are secured, said stem ends and filler strips forming a base for the assembly spacing the matches clear from both sides of the hood, and a

pivot pin extending centrally through said sides of the hood and said base and securing the base between said ends of the hood for swinging movement of the assembly out of and into the hood, the sides of the hood having beveled corner edges exposing a portion of said base for engagement by a finger to swing the assembly out of the hood,

5 said base having an edge match scratching strip thereon fitting flush with said ends of the hood when said assembly is swung into the hood, whereby matches may be scratched crosswise of said scratching strip at any point along the same when the assembly is swung into the hood.

ALFRED FRANKLIN HODGES.
